Pennsylvania

Filed Mar. 5, 1965, Ser. No. 84,120

Term of patent 14 years

(Cl. D15—11)

The dominant features of my design reside in those portions shown in full lines.

I claim:

The ornamental design for a sofa, as shown and described.
